Des. 218,152
Patented July 28, 1970

218,152

CONTAINER FOR XEROGRAPHIC POWDER

William C. Emerson, Rochester, N.Y., assignor to Xerox
Corporation, Rochester, N.Y., a corporation of New
York

Filed Feb. 6, 1969, Ser. No. 15,677

Term of patent 14 years

Int. Cl. D9—99

U.S. Cl. D9—207

FIG. 1

FIG. 2

FIG. 3

FIG. 4

FIG. 5

FIG. 1 is a front perspective view of a container for xerographic powder showing my new design;

FIG. 2 is a rear elevation view;

FIG. 3 is an end elevation view looking from the left in FIG. 2;

FIG. 4 is an end elevation view looking from the right in FIG. 2; and

FIG. 5 is a bottom view of the container for xerographic powder illustrated in FIG. 2.

I claim:

The ornamental design for a container for xerographic powder, as shown.
